ATTORNEY

UNITED STATES PATENT OFFICE.

AUGUST EBERLE, OF HAMILTON, OHIO.

CASTER.

SPECIFICATION forming part of Letters Patent No. 292,797, dated February 5, 1884.

Application filed July 5, 1883. (Model.)

To all whom it may concern:

Be it known that I, AUGUST EBERLE, of Hamilton, Butler county, Ohio, have invented certain new and useful Improvements in Casters, of which the following is a specification.

This invention relates to furniture-casters of that class in which the housing is arranged to oscillate with reference to the furniture to which the caster may be attached, as well as to swivel around a vertical pivot.

The nature of the invention will be understood from the following description and the accompanying drawings, in which—

Figure 1 is a side view of a caster embodying my improvements; Fig. 2, a vertical section, viewed from the side; Fig. 3, a rear view; Fig. 4, a front view, and Fig. 5 a perspective view with the floor-wheels omitted.

In the drawings, A represents a flange to attach to furniture; B, a central top boss on this stem; C, a central under boss on the stem; D, the wheel-housing; E, the two floor-wheels; F, a curtain forward of the wheels, pendent from the roof of the housing; G, a similar curtain nearer the axis of the floor-wheels; H, a block fitting between the curtains at their lower ends; I, a pin or rivet passing through the block and through the bosses B C and securing the block to the flange-piece; J, a journal of the front of the block, fitting a bearing-hole in the foot of the front curtain; K, a journal on the rear of the block, fitting a half-bearing in the rear curtain, G, and prolonged to the rear to pass over the wheel-axle between the inner hubs of the wheels; L, the wheel-axle, and M a slot in the roof of the housing for the admission and free movement of the boss C.

The pin I forms the axis of the housing as it swivels upon the furniture. The pin may be fitted loosely in the block or in the bosses, or in both; or it may be prolonged above into an attaching-screw to engage the furniture. The flange A and boss B form simply a means for connecting the pin I with the furniture, and I contemplate the substitution of other suitable usual means. The foot of boss C bears upon the top of the block. The block, with its two journals fitting the curtains, permits the housing to oscillate with reference to the pin and the furniture to which the pin is attached, whereby the two wheels are enabled to secure an equable bearing upon the floor.

55 The half-bearing at the foot of curtain G

saves drilling and permits the ready insertion of the block with its journals. The prolongation of the journal K over the wheel-axle serves to give a central support to the axle, thus avoiding a central housing-hanger. The 60 location of the axis of the oscillating movement low down near the axis of the wheels permits the proper oscillation of the housing without danger of cramping.

Instead of the block being provided with 65 journals formed upon it and fitted with a separable vertical pin, as shown, the vertical pin may be formed with the block and the journals of oscillation secured by an inserted rivet or pin, and the block, instead of bearing directly against the boss C to receive the weight of the furniture, may support the weight by means of its vertical stem having a thrust-bearing up in a socket in the furniture, as is 70 common in swiveling casters.

75 I claim as my invention—

1. The housing D, having the two curtains pendent from its roof, and the vertical pin I, provided with means for connection to furniture, and joined to the foot of the curtains by 80 a horizontal axle of oscillation, combined substantially as and for the purpose specified.

2. The housing D, having curtain F and curtain G, with a half-bearing, the block H, with 85 its journals, and the pin I, combined substantially as and for the purpose specified.

3. The housing D, with its curtains F G and slot M, the block H, with its journals, the pin I, provided with means for attachment to furniture, and the boss C, resting on the block, 90 combined substantially as and for the purpose specified.

4. The housing D, the wheel-axle L, the two wheels E, the pin I, provided with means for connection to furniture, the curtains F G, 95 pendent from the roof of the housing, and the axle of oscillation prolonged to the rear between the wheel-hubs and over the wheel-axle, combined substantially as and for the purpose specified.

100 5. The flange A, having bosses B and C, the housing D, having curtains F and G, the block H, having journals J and K, and the riveted pin I, combined substantially as and for the purpose specified.

AUGUST EBERLE.
